POULTRY BROODER

Percy M. Forster, Berkeley, Calif.

Application March 7, 1933, Serial No. 659,913

5 Claims. (Cl. 119—32)

This invention relates to a brooder hover for use in raising poultry.

It is the principal object of the present invention to provide a hover of the character referred to which is of inexpensive construction and which will evenly and properly distribute heated air from a centrally located source over a considerable area to be occupied by the chicks.

In carrying the invention into practice, I provide a central heating chamber in which heat may be generated by any suitable type of burner. Overlying this heating chamber is a frusto-conical hood, the base of which is open and beneath which the chicks may hover. The interior of this hood is divided into annular air passages opening at the base of the hood, so that the heat generated in the heating chamber will be directed downwardly through these passages toward the chicks hovered therebeneath. By this medium the heated air will be distributed over the entire area covered by the hood.

One form which the invention may assume is exemplified in the following description and illustrated by way of example in the accompanying drawing, in which:

Fig. 1 is a central vertical section through a hover constructed in accordance with my invention, taken on line I—I of Fig. 2.

Fig. 2 is a plan section taken on line II—II of Fig. 1.

Referring more particularly to the accompanying drawing, 10 indicates a brooder hover for use in raising poultry. This hover is constructed almost entirely of sheet metal and is consequently inexpensive to manufacture.

The hover comprises a central cylindrical shell 11 which encloses a heating chamber 12. The lower end of the shell 11 is flanged as at 14 to form a base for supporting the hover in a properly erect position. The base so formed may, if desired, be secured to the floor of the brooder or may be of such an area and formation as to support the hover without such fastening. The shell 11 is provided with a number of openings 11a as illustrated.

Arranged within the heating chamber 11 is a burner, indicated at 15, which may be of any suitable type. I am aware that I may use an electric burner or a burner which will operate on natural gas, manufactured gas or liquefied petroleum gas. However, there are other types of burners and fuels which may be employed with equal efficiency in my present hover.

It will be noticed that the upper end of the shell 11 is open so that the heat generated within the

heating chamber 12 may freely rise and discharge upwardly from the heating chamber 12.

Overlying the shell 11 and the heating chamber 12 and arranged in concentric relation thereto is a frusto-conical hood 16. The base of this hood 16 is open while the upper end of the hood is closed by an imperforate top plate 17. It will be noticed that the hood is formed of two frusto-conical shells secured together at their ends to form a heat insulating air space therebetween to minimize heat losses by radiation.

Arranged interiorly of the hood beneath the top plate 17 is a convex baffle plate 18. This plate is secured at its periphery to the top plate 17 and the hood 16 at the junction therebetween. The convexity of the baffle plate 18 forms a heat insulating air space between it and the top plate 17 so as to minimize heat losses by radiation at the top of the hood. The baffle plate 18 tends to deflect the heated air rising from the heating chamber 12 and to direct the same downwardly through the space between the hood 16 and the shell 11.

Reference being had particularly to Fig. 1, it will be noted that at its base the hood is formed with a depending annular flange 19, the lower edge of which is on a plane spaced vertically from the plane on which the lower end of the shell is disposed, in order that the chicks may hover about the shell 11 beneath the hood.

It will be noticed that the upper open end of the shell 11 is positioned at a distance below the top of the hood in order that the heated air arising from the heating chamber 12 may be directed downwardly toward the space which the hood 16 overlies.

In order that the heated air will be distributed over this space and maintain an even temperature throughout the space occupied by the chicks, I provide a plurality of open-ended frusto-conical partition members 20. These partition members 20 progressively decrease in dimensions from the hood 16 to the cylindrical shell 11 so as to form a plurality of annular air passageways 21 between the hood and the shell 11. The bases of the partition members 20 are disposed on the same plane as the base of the hood, and each partition member 20 is formed with a circular or annular flange 22 which depends from the bases of the partition members the same as the flange 19 depends from the base of the hood 16. The upper ends of the partition members 20 terminate at progressively increasing heights above the plane of the base of the hood.

Surrounding the shell 11 at a spaced distance

therefrom is a partition 23 which intersects the innermost frusto-conical partition 20 at its upper end. The lower end of this partition 23 terminates a short distance above the plane of the bases of the partitions 20.

At a point substantially at the plane of the bases of the partitions 20 is a frusto-conical flange 24 which is fitted to the shell 11. This flange 24 tends to deflect heated air passing downwardly 10 through the passageway 25 between the partition 23 and the shell 11 into the space between the shell 11 and the base of the innermost frusto-conical partition 20.

The hood 16, the partition members 20 and 23 and the shell 11 are all rigidly interconnected and fastened together to form a rigid and durable structure.

In operation a heater or burner of any preferred type is arranged in the shell just above its lower end and through an opening formed in an intermediate plate 26 arranged transversely in the shell 11. If desired, the portion of the shell below the plate 26 may be in the form of legs or stand although in the present instance I have shown it as a continuation of the shell 11 proper.

As heat is generated in the heating chamber 12, heated air will rise toward the top of the hood and will be deflected downwardly toward the open upper ends of the passageways 21 and 25. It will pass downwardly through these passageways and be discharged at their lower ends in a perfectly straight downward direction toward the chicks hoovered therebeneath.

It is obvious that by this means the heated air will be distributed throughout the entire area between the base of the hood 16 and the shell 11, and that the chicks hoovered beneath the hood will all be subjected to the same even and proper temperature.

It is desired to call attention to the fact that when the partitions 20 and 23 become heated, they will radiate heat and consequently increase the efficiency of the hoover.

It is obvious from the foregoing that I have provided an efficient hoover for use in raising poultry and that the same will be inexpensive to manufacture and will be economical to operate, and while I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A brooder hoover comprising a shell forming a heating chamber, a frusto-conical hood supported by said shell and overlying the heating chamber, the upper end of the hood being closed, the base of the hood being open, said hood being arranged concentrically of the shell, the periphery of the base of the hood being considerably larger in diameter than the transverse dimension of the shell, the upper end of the hood being spaced above the heating chamber whereby heated air from the heating chamber will be directed downwardly through the space between the periphery of the hood at the base thereof and the shell, and baffle means arranged intermediate the hood and the shell forming a plurality of annular air passageways therebetween through which the heated air will be directed, said passageways terminating at the base of the hood so as to distribute the air through the space between

the periphery of the hood at the base and the shell.

2. A brooder hoover comprising a shell forming a heating chamber, a frusto-conical hood supported by said shell and overlying the heating chamber, the upper end of the hood being closed, the base of the hood being open, said hood being arranged concentrically of the shell, the periphery of the base of the hood being considerably larger in diameter than the transverse dimension of the shell, the upper end of the hood being spaced above the heating chamber whereby heated air from the heating chamber will be directed downwardly through the space between the periphery of the hood at the base thereof and the shell, and a plurality of open-ended frusto-conical partition members of progressively decreasing diameters arranged intermediate the hood and shell and rigidly supported thereby and arranged with their bases disposed on the same plane as the base of the hood, the upper ends of the partition members terminating short of the top of the hood whereby to form a plurality of annular air passageways between the hood and the shell to direct the heated air downwardly through the base of the hood and distribute the same over the area between the periphery of the hood at the base thereof and the shell.

3. A brooder hoover comprising a central shell forming a heating chamber, means for supporting the same in a vertical position, a frusto-conical hood overlying the open upper end of the shell and supported thereby in concentric relation thereto, the upper end of the hood being closed, the base of the hood being open, the base of the hood being spaced vertically from the supporting means of the shell whereby chicks may hoover beneath the hood, a plurality of open-ended frusto-conical partition members arranged within the space between the hood and shell, said partition members being of different dimensions whereby to provide a plurality of similar annular air passages in the space between the hood and the shell whereby heated air from the heating chamber will rise in the hood and be directed downwardly through the base of the hood through said air passages, the bases of said partition members lying in the same plane as the base of the hood whereby to direct the air over the area between the periphery of the hood at its base and the shell, and annular flanges at the base of the hood and the bases of the partitions, said flanges depending in order to direct the air passing through said air passages in a downward direction.

4. A brooder hoover comprising a central shell forming a heating chamber, means for supporting the same in a vertical position, a frusto-conical hood overlying the open upper end of the shell and supported thereby in concentric relation thereto, the upper end of the hood being closed, the base of the hood being open, the base of the hood being spaced vertically from the supporting means of the shell whereby chicks may hoover beneath the hood, a plurality of open-ended frusto-conical partition members arranged within the space between the hood and shell, said partition members being of different dimensions whereby to provide a plurality of similar annular air passages in the space between the hood and the shell whereby heated air from the heating chamber will rise in the hood and be directed downwardly through the base of the hood through said air passages, the bases of said partition

members lying in the same plane as the base of the hood whereby to direct the air over the area between the periphery of the hood at its base and the shell, and baffle means forming an air passage around the shell and for directing heated air into the space between the periphery of the innermost partition and the shell, said hood and partition members being formed with depending annular flanges at their bases to direct the currents of air passing through said passages directly downward at the base of the hood.

5 A brooder hover comprising a central shell forming a heating chamber, means for supporting the same in a vertical position, a frusto-conical hood overlying the open upper end of the shell and supported thereby in concentric relation thereto, the upper end of the hood being closed, the base of the hood being open, the base of the hood being spaced vertically from the sup-
10 porting means of the shell whereby chicks may

hover beneath the hood, a plurality of open-ended frusto-conical partition members arranged within the space between the hood and shell, said partition members being of different dimensions whereby to provide a plurality of similar annular air passages in the space between the hood and the shell whereby heated air from the heating chamber will rise in the hood and be directed downwardly through the base of the hood through said air passages, the bases of said partition members lying in the same plane as the base of the hood whereby to direct the air over the area between the periphery of the hood at its base and the shell, baffle means within the top of the hood for directing the heated air downwardly through said passages, and annular depending flanges at the bases of the hood and partitions to direct the air straight downwardly at the base of the hood.
